Design No. 17,750, dated September 27, 1887.

UNITED STATES PATENT OFFICE.

CATHERINE SHEILS, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 17,750, dated September 27, 1887.

Application filed August 8, 1887. Serial No. 246,459. Term of patent 3½ years.

To all whom it may concern:

Be it known that I, CATHERINE SHEILS, of the city, county, and State of New York, have invented and produced a new and original Design for a Pattern of a Girl's Costume; and I do hereby declare that the engraved prints accompanying this specification convey to any one accustomed to using paper patterns a clear understanding of how a garment made up by the pattern will appear.

The design shows a dress and a jacket. The dress displays a skirt that exhibits a triple box-plaited drapery on its front, and full back draperies that display rounding back edges flaring shapely, and straight plaits at their front edges, where they fall to the edge, and a plaited vest ornament on the front of the waist

falling over the top of the skirt. The jacket displays loose-fitting fronts flaring from the throat and exhibiting wide three-cornered revers at their front edges nearly to the lower edge, a close-fitting back that displays plaits in the lower part of the side-back seams, a standing collar, and coat-sleeves.

What I claim as my invention, and desire to secure by Letters Patent, is—

The design for a girl's costume, as shown in the engraved print accompanying this specification.

CATHERINE SHEILS.
